United States Patent Office

Des. 210,257

Patented Feb. 20, 1968

210,257

MAIL BOX UNIT

Alfonso Favaro, Via Pola 13, Turin, Italy

Filed Sept. 30, 1965, Ser. No. 87,233

Term of patent 14 years

(CL. D74—9)

Fig.1

Fig.2

FIGURE 1 is a perspective view of a mail box unit showing my new design; and

FIGURE 2 is a rear elevational view of one door thereof, the center of which is broken away for convenience of illustration.

The bottom, rear and side opposite that shown in FIGURE 1 are plain.

I claim:

The ornamental design for a mail box unit, as shown and described.
